CENTRIFUGAL PUMP

Russell L. Hoelzer, Fairview Park, and George J. Schmidt, Cleveland, Ohio, assignors to The Dow Chemical Company, Midland, Mich., a corporation of Delaware
Filed June 17, 1960, Ser. No. 36,864
6 Claims. (Cl. 101—366)

This invention relates to centrifugal pumps, and more particularly to a centrifugal pump for use in lifting abrasive and/or corrosive liquids a predetermined distance.

Centrifugal pumps generally have an impeller with radial or curved vaned surfaces, the impeller being mounted upon a shaft and housed in a cavity of volute conformation. The impeller is necessarily closely fitted in the housing cavity and mounted upon a shaft carried on bearings, while some type of seal means is generally provided. Rapid wear of the impeller, housing cavity, bearings and seal means will occur when the liquid being pumped is of an abrasive and/or corrosive nature. In addition, it is impossible to keep the bearings and seal means adequately lubricated because solvents contained in the liquid being pumped, wash away the lubricants, which also can contaminate the liquid being pumped.

While the centrifugal pump of the invention may be advantageously used in many applications, it will be found especially well suited for use in certain types of printing presses. Pumps generally used for circulating solvent type inks and coatings in the ink fountain of flexographic and gravure printing presses, are costly, involve excessive maintenance due to wear and corrosion of seals and impellers, contaminate the ink with lubricant and foreign particles, and require frequent lubrication. Constant circulation of the ink is important for maintaining uniform color and consistency.

The centrifugal pump of the invention avoids the disadvantages and shortcomings of centrifugal pumps generally used on printing presses. More particularly, the centrifugal pump of the invention incorporates the following features: no close fitting parts, thus eliminating wear; no contact or exposure of the ink to seals, bearings, or lubricants, hence, these elements of the pump, as well as the ink being circulated, are free of contamination; the pump is simple in structure, thus allowing low cost manufacture, and easy assembly and disassembly for cleaning, and, the pump is adaptable for direct mounting upon the ink fountain of a printing press, thereby eliminating hoses, tanks, and buckets generally required by printing press pumps of the prior art.

Briefly, the centrifugal pump of the invention includes a smooth conical rotor, the upper end of which is closed, and has a plurality of openings about the periphery thereof, while the lower end of the rotor is positioned for immersion in the ink to be circulated. A collector cup is arranged about the upper end of the rotor, which cup has a pitcher spout through which the ink can pass by gravity to an ink fountain of the printing press. The pump operates on the simple principle of centrifugal force, whereby rapid rotation of the rotor causes the ink to be lifted upwardly and outwardly through the openings at the upper end of the rotor. The pump operates only to lift liquid a given amount; there is no pressurization of the liquid being pumped. The volume of liquid to be pumped may be varied by regulating of rotor speed. The rotor is preferably rotated by an air motor, when the pump is used in the vicinity of inflammable solvents, such as are commonly used in printing inks.

The main object of this invention is to provide a centrifugal pump for use in handling abrasive and/or corrosive liquids.

A more specific object of this invention is to provide a centrifugal pump for handling abrasive and/or corrosive

2

liquids, which pump has no close fitting parts, thus avoiding wear on the operative parts of the pump.

Another object of this invention is to provide a centrifugal pump for handling abrasive and/or corrosive liquids wherein the liquid being handled is free from contact or exposure to seals, bearings, or pump lubricants, thus avoiding contamination of the pump parts, as well as the liquid being circulated.

Still another object of this invention is to provide a centrifugal pump which eliminates the need for hoses, tanks and buckets generally used with pumps when applied upon the ink fountains of certain printing presses.

Another object of this invention is to provide a centrifugal pump which is simple in structure, thus allowing low cost manufacture, and easy assembly and disassembly.

These and further objects and features of the invention will become more apparent from the following description and the accompanying drawing wherein:

FIG. 1 is an elevation view, substantially in cross-section, illustrating a centrifugal pump representing an embodiment of the invention, which pump is shown as applied to a printing press; and,

FIG. 2 is a section view generally as seen along line 2—2 in FIG. 1.

Referring now to the drawing, the numeral 10 identifies a pump assemblage which includes a rotor assembly 12, and a collector cup 14. The rotor assembly 12 includes a rotor in the form of a smooth conical cylindrical member 16 which tapers toward an opening at the lower end, the upper end of the rotor being formed to provide a cylindrical enlargement 18, and a hub member 20 which encloses the upper end of the rotor 16 and to which the rotor is securely affixed for vertical suspension. The taper of the rotor 16 may be set according to pump, or lifting effect desired; in the disclosed application of the pump, a taper of approximately 5° was found to provide satisfactory results. While the rotor has been described as having a "smooth" surface, it may be desirable, under certain conditions, to employ a surface that is not exactly smooth.

In any event, the main objective is to employ a rotor configuration which will develop a lifting force upon the liquid as the rotor is caused to rotate. The lower surface of the hub member 20 is tapered whereby an apex 22 thereof will coincide with the longitudinal centerline of the rotor 16. A plurality of equi-spaced holes, or openings 24 are provided in the side wall of the rotor cylindrical enlargement 18, the upper edge of said openings coinciding with the outer edge of the tapered surface formed on the hub 20.

The collector cup 14 is formed to provide a flanged hole 26, the flange thereof extending upwardly and in spaced relation to the exterior of the rotor 16. A side portion of the collector cup is formed to provide a "pitcher spout" 28, which extends outwardly from the wall of the collector cup to provide an opening 30 which is co-extensive with the lower surface of the collector cup.

A closure ring, or cover means 32 is securely affixed to the collector cup 14 at the upper end thereof, which closure ring is adapted to support a motor means assembly 34. The motor assembly 34 includes a shaft 36, to which is secured a hub 38 adapted to receive in snug engagement, the rotor hub member 20. Holding means, such as set screws 40 may be used to secure the hub member 20 to the hub 38. The motor means 34

may be of any type as will provide high speed rotation of the shaft 36, however, when the centrifugal pump of the invention is being used to handle inflammable, or explosive liquids, the use of an explosion proof motor, such as an air motor would naturally be recommended.

In the illustrated arrangement, an air motor 42 is utilized which is supplied with compressed air via a conduit, or pipe arrangement 44.

While the centrifugal pump of the invention will be found to be extremely well suited for many applications, especially wherein the liquid to be handled is of an abrasive and/or corrosive nature, it will be described as applied to a printing press for circulating solvent type inks and coatings, as used in flexographic and gravure printing. As seen in FIG. 1, a pair of inking rolls, or rollers 46 and 48 are arranged in rolling engagement, while a pan means 50 is supported beneath the ink rolls by a pair of rod means 52, 54. The pan means 50 includes an ink fountain portion 56, and a sump portion 58. The fountain portion 56 is adapted for maintenance of printing ink at a constant level to assure a steady supply of ink to the roll 48 which is partially immersed therein. Any ink supply to the fountain 56 in excess of predetermined requirements will flow into the sump portion 58, as will be readily apparent.

The pump assemblage 10 is affixed to an adjustable mounting bracket assemblage 60 which is clamped upon the pan means 50 so that the lower end of the rotor 16 is immersed in the ink supply in the sump portion 58, while the pitcher spout 28 is arranged to discharge ink into the fountain portion 56. A shield in the form of a cylindrical tube 62, may be affixed to the bracket assembly in concentric spaced relation to the rotor 16, which shield 62 extends downwardly a given distance below the surface of the ink in the sump portion 58.

The operation of the centrifugal pump of the invention is extremely simple for the pumping and circulating of printing ink. The pump operates on the simple principle of centrifugal force; rapid rotation of the rotor 16 causes the ink to be lifted upwardly within the rotor and discharged or expelled radially through the rotor openings 24. The ink thus expelled, will be caught in the collector cup from whence it will flow by gravity through the spout opening 30 into the ink fountain 56. The volume of liquid to be pumped or circulated, may be easily regulated by controlling the speed of the motor 42, which, in the case of an air motor, involves no more than the adjustment of an air flow valve.

From the foregoing, it will be appreciated that the centrifugal pump of the invention may be used to realize all of the objectives set forth in the early part of this disclosure.

The foregoing description has been given in detail without thought of limitation, since the inventive principles involved are capable of assuming other forms without departing from the spirit of the invention or the scope of the following claims.

What is claimed is:

1. A centrifugal pump for raising liquids including, a hollow rotor having a smooth interior surface which tapers toward an opening at the lower extremity, a hub means at the upper extremity of the rotor, said hub means being arranged for the vertical suspension of said rotor, said rotor being formed to provide openings adjacent said hub means to allow radial discharge of liquid raised upwardly within the rotor due to rotation thereof, and a collector cup surrounding the upper end of said rotor for receiving the liquid discharged from said openings, said collector cup being formed to provide an opening to allow egress of liquid therefrom.

2. A centrifugal pump for raising liquids including, a smooth interior hollow conical rotor tapering toward an opening at the lower extremity and having a cylindrical enlargement at the opposite extremity, a hub means secured to and enclosing said cylindrical enlargement and being arranged for the vertical suspension of the rotor,

said rotor being formed to provide openings adjacent said hub means to allow radial discharge of liquid raised upwardly within the rotor due to rotation thereof, and a collector cup surrounding the upper end of said rotor for receiving the liquid discharged from said openings, said collector cup being formed to provide a flanged opening for receiving in spaced relation said rotor and being further formed to provide an opening to allow egress of liquid from the collector cup.

3. A centrifugal pump for raising liquids including, a smooth interior hollow conical rotor tapering toward an opening at the lower extremity and having a cylindrical enlargement at the opposite extremity, a hub means secured to and enclosing said cylindrical enlargement and being arranged for the vertical suspension of the rotor, said rotor being formed to provide a plurality of openings adjacent said hub means to allow radial discharge of liquid raised upwardly within the rotor due to rotation thereof, a collector cup surrounding the upper end of said rotor for receiving the liquid discharged from said openings, said collector cup being formed to provide a flanged opening in spaced relation to said rotor the flange of which extends upwardly, said collector cup being further formed to provide an opening to allow egress of liquid from the collector cup, and a cover means for said collector cup, said cover means being arranged for support of a motor means operable for rotation of said rotor.

4. A centrifugal pump according to claim 3, wherein a shield means in the form of a cylindrical tube is arranged below the collector cup and in spaced relation to said rotor.

5. A printing press roll inking arrangement comprising in combination, an inking roller, a constant level ink fountain which forms part of a pan means including a sump portion which receives overflow ink from the ink fountain, a rotor assembly including a smooth interior hollow conical rotor tapering toward an opening at the lower extremity and having a cylindrical enlargement at the opposite extremity, a hub means secured to and enclosing said cylindrical enlargement and being arranged for the vertical suspension of the rotor, said rotor being formed to provide a plurality of openings adjacent said hub means to allow radial discharge of liquid raised upwardly within the rotor due to rotation thereof, a collector cup surrounding the upper end of said rotor for receiving the liquid discharged from said openings, said collector cup being formed to provide a flanged opening in spaced relation to said rotor, the flange of said opening extending upwardly, said collector cup being further arranged to provide a pitcher spout having an opening which is positioned above the ink fountain, and a bracket means for supporting the centrifugal pump assemblage so that the lower end of the rotor will be immersed in a body of ink in the sump portion.

6. A centrifugal pump according to claim 5, wherein a cover means is arranged atop said collector cup, which cover means is adapted for the support of a motor means operable for rotation of said rotor.
